UNITED STATES PATENT OFFICE.

JOSEPH W. SCHLOSS AND MEYER W. SCHLOSS, OF NEW YORK, N. Y., ASSIGNEES TO
CASTLEBONE COMPANY, A CORPORATION OF NEW YORK.

DISPENSING-CONTAINER.

1,154,212.

Specification of Letters Patent. Patented Sept. 21, 1915.

Application filed December 31, 1914. Serial No. 879,840.

To all whom it may concern:

Be it known that we, JOSEPH W. SCHLOSS and MEYER W. SCHLOSS, citizens of the United States, residing at New York city, in the borough of Manhattan and State of New York, have invented certain new and useful Improvements in Dispensing-Containers, of which the following is a full, clear, and exact description.

10 This invention relates to dispensing containers for flat rolls of featherbone, tape and like material, and has for its primary object the provision of a box or package which will completely house the roll and yet permit 15 a length of the material to be drawn from the box or rewound upon the roll with marked ease and facility without removing the roll from the box.

Accordingly, my invention contemplates 20 utilizing a package for the roll, which is closed after the roll has been once inserted therein, and which is provided with a slot through which the end of the roll extends, and in forming in the same or different faces 25 of the box a pair of openings through which a person may insert his fingers to rotate the roll and hence rewind a loose length of material thereon. These finger openings are obviously smaller than the roll, which, therefore, 30 is completely housed but is readily accessible when it is desired to rewind a loose length of the material upon it.

Another object of the invention is to provide 35 a box or package of the character just referred to from a single blank of sheet material, which produces a simple and cheap form of package desirable for use as a container for rolls of material whose intrinsic value is relatively small. This blank is preferably 40 cut and folded so that it will form a supplemental cover which will close the finger openings in the package.

With these and other objects in view which will be apparent from the detailed description, 45 the invention consists of the combinations and constructions hereinafter to be described and particularly set forth in the appended claims.

In the accompanying drawings, Figure 1 50 shows in perspective my improved form of container, the cover being in closed position;

Fig. 2 is a plan view of the package with the cover in open position; and Fig. 3 is a plan of the blank which is used to construct the preferred embodiment of the container. 55

The container which is to be hereinafter described is particularly suitable for dispensing flat rolls of tape, braid, featherbone and the like, in flat form, the one shown being especially designed for dispensing 60 featherbone. This material while elastic, cannot, owing to its stiffness, be wound upon a reel, since after a length has been cut from the roll the remaining coils expand until the external diameter of the roll is the same 65 as the container, which would cause the inner coils to leave, or to be so loosely wound upon, a reel as to make the latter valueless. While the package is suitable for rolls of braid or tape made from soft material, yet 70 to be used with the same it would be necessary to wind the same upon a reel and mount the reel within the package, under which circumstances the form of container which is to be described could be used to advantage. 75

Referring to the drawings, the box or container has been illustrated as containing a roll of featherbone, a portion of which shows through the openings in the top face 80 of the box in Fig. 2, and has been designated 1. The box or package which is designated 2 is, broadly speaking, of the usual shape which is ordinarily used for this purpose, and is of a suitable length, width and depth 85 to receive a roll of featherbone of the desired size. Instead, however, of having an open top, as has heretofore been the invariable practice, the same is closed by a diaphragm 3 which may or may not be formed 90 integral with the sides and bottom of the box, and which, together with these parts, form a closed package which entirely incloses the roll of featherbone so that after it is once placed within the same it may remain there until entirely used up. In one of the side walls of the box a slot or opening 4 is provided through which the loose end of the roll is adapted to pass so that when desired the same may be grasped and any 100 desired length withdrawn for use. To provide access to the roll, finger openings are

provided which are preferably cut in the diaphragm, one of these openings consisting of a central finger opening 5 preferably of but slightly greater diameter than the inner 5 diameter of the roll, which will effectually prevent any tendency of the inner coils of the roll to fly out through this opening after the roll is partially exhausted, for after a portion of a full roll has been used 10 the internal diameter of the roll increases, since the coils expand to take up the space which was formerly occupied thereby. Spaced from this central opening 5 is a second finger opening 6 which is preferably arranged adjacent one of the corners of the 15 box, which, together with the opening 5, provides a means of access to the interior of the box through which the thumb and forefinger of a person may be inserted to grasp 20 the roll between them, and rotate the same to rewind upon the roll a surplus length of featherbone which has been withdrawn from the box.

It is of course understood that the opening 25 6 is of sufficient size to permit a relative movement of the finger therein to permit the roll to be turned. Other openings 7 may be provided in the box which are symmetrically arranged with respect to the openings 5 and 30 6. These openings also may be used as finger openings but will also serve as display openings through which a portion of the roll of featherbone is exposed to view. In order to protect the roll of featherbone 35 from being soiled, a cover 8 is provided for the closed package, which, when in closed position as shown in Fig. 1, effectually prevents the entrance of dust or dirt through the finger openings. This cover may be of 40 any suitable shape and may be integral with the box if so desired, as will be hereinafter referred to.

In order to obtain a box of this construction at a greatly reduced cost the form of 45 blank shown in Fig. 3 may be utilized. Here the top face or diaphragm is designated 3 as before, the side walls 9, 10, 11 and 12 respectively, the bottom 13, and the cover 8. Attached to the top face or diaphragm is a 50 flap 14, while attached to the side walls 9 and 10 are flaps 15, and laterally projecting from the end walls 11 and 12 are the flaps 16. In order to construct the box from this blank the various side walls and faces of the 55 flaps are folded along the lines shown, or in other words, the blank is folded over until the flap 14 is adjacent the inner face of the side wall 10 to which it is then secured by paste, or in any other manner. The flaps 60 15 are then folded inwardly and one of the end walls, as for example 11, with its attached flap 16, is also folded in so as to close one end of the box; the other end wall 12, however, is not folded into place until a

full roll of featherbone has been inserted in 65 the box, when it is then folded into position, and the full roll is inclosed within a closed package having finger openings 5, 6 and 7 in its top face, which are protected by means of the cover 8 integral with the remaining 70 portions of the box. The opening 4 is also cut in one of the side walls when the blank is stamped out.

A box constructed in this manner may be produced at a greatly reduced cost and need 75 only be made of comparatively light stock, since when the package with the roll inside it has once been assembled, the fact that it forms a closed package will give it the necessary stiffness. Another advantage which may be 80 noted is that the advertising matter may be printed simultaneously and directly on the top face of the diaphragm 3 and the outer face of the cover 8, obviating the necessity for labels which have heretofore been used. 85

Claims.

1. A dispensing container for coreless rolls of material, comprising a closed package inclosing the roll, having a slot therein through which the loose end of the roll is 90 adapted to pass, and a pair of spaced finger openings in the top face of the box affording access to the interior and exterior peripheries of the roll to rotate the same.

2. A dispensing container for coreless 95 rolls of material, comprising a closed package inclosing the roll, having a slot therein through which the loose end of the roll is adapted to pass, a pair of spaced finger openings in the top face of the box afford- 100 ing access to the interior and exterior peripheries of the roll to rotate the same, and a cover for the top face of said package covering said finger openings.

3. A dispensing container for flat annular 105 coreless rolls of material, comprising a closed package inclosing the roll having a slot therein through which the loose end of the roll is adapted to pass, and having a centrally disposed opening and an opening 110 spaced therefrom in the top face of the package affording access to the inner and outer peripheries of said roll.

4. A dispensing container for flat annular 115 coreless rolls of material, comprising a closed package inclosing the roll having a slot therein through which the loose end of the roll is adapted to pass, and having a centrally disposed opening and an opening 120 spaced therefrom in the top face of the package affording access to the inner and outer peripheries of said roll, and a cover for covering the top face of said package.

5. In combination with a flat coreless roll 125 of featherbone and the like, a dispensing container therefor comprising a box formed from a flat blank cut and folded to provide a six-sided rectangular closed package hav-

ing a movable end wall through which the roll is inserted into the box, one of the faces of said box having openings therein affording access to the inner and outer peripheries of said roll, and a cover for said last named face forming a part of said blank and integral with one of the side walls of said package.

In witness whereof, we subscribe our signatures, in the presence of two witnesses.
